UNITED STATES PATENT OFFICE.

JOHN P. CLARY VON CARLSBERG, OF WORCESTER, MASSACHUSETTS.

DESIGN FOR A LUNCHEON-TABLE.

51,943.

Specification for Design.

Patented Apr. 2, 1918.

Application filed October 24, 1917. Serial No. 198,319. Term of patent 7 years.

To all whom it may concern:

Be it known that I, JOHN P. CLARY VON CARLSBERG, a citizen of the United States of America, residing at Worcester, in the county of Worcester and State of Massachusetts, have invented a new, original and ornamental Design for a Luncheon-Table, of which the following is a specification, reference being had to the accompanying drawing, forming part thereof.

The figure is a view in perspective of a luncheon table, showing my new design.

I claim:—

The ornamental design for a luncheon table, as shown.

JOHN P. CLARY VON CARLSBERG.
